OTHER PUBLICATIONS

Deneve®, Solar Flag Pole Flagpole Light, Version 1.0, for sale at least by Apr. 2014.

Primary Examiner — Clare E Heflin(74) *Attorney, Agent, or Firm* — Knobbe Martens Olson & Bear LLP(57) **CLAIM**

The ornamental design for a flag pole light, as shown and described.

DESCRIPTION

FIG. 1 is a bottom perspective view of a flag pole light embodying my new design, wherein the darkened areas depict a reflective surface;

FIG. 2 is a top perspective view thereof, wherein the darkened areas depict a reflective surface;

FIG. 3 is a bottom view thereof, wherein the darkened areas depict a reflective surface;

FIG. 4 is a top view thereof;

FIG. 5 is a front view thereof, wherein the darkened areas depict a reflective surface;

FIG. 6 is a back view thereof, wherein the darkened areas depict a reflective surface;

FIG. 7 is a first side view thereof, wherein the darkened areas depict a reflective surface; and,

FIG. 8 is a second side view thereof, wherein the darkened areas depict a reflective surface.

The bottom surface of the flag pole light is shaded to depict a reflective surface.
